POWER OPERATED KNIFE WITH ADJUSTABLE BLADES

Robert M. Peterson, Racine, Wis., assignor to Scovill Manufacturing Company, Waterbury, Conn., a corporation of Connecticut

Filed June 25, 1965, Ser. No. 466,954
10 Claims. (Cl. 30—272)

This invention relates to power operated slicing knives, and particularly to a knife adapted for slicing meat and other foods or materials by blades disposed in either vertical or horizontal cutting positions while the user holds the knife in a predetermined position without rotating the body of the knife as a whole about its longitudinal axis in order to change the cutting position of the blades.

Power operated knives on the market commonly are provided with elongated generally cylindrical housings shaped to be gripped in the hand of a user in a predetermined position wherein the blade are disposed in vertical planes and are adapted for slicing by cutting in vertical planes. If the user of such a knife desires to slice in a horizontal plane, it is necessary to turn or rotate the knife bodily about its longitudinal axis in order to place the blades at the desired angle. This rotation of the knife body from its initially designed position deprives the user of the benefit of the shape or configuration of the knife body which was originally provided to aid the user in grasping and holding the knife with the blades in vertical planes.

Also on the market is a power operated knife provided with an elongated body and a handle connected to the upper wall of the body, as shown in U.S. Design Letters Patent No. 200,905, assigned to the assignee of this application. When held by grasping the handle, the body naturally depends from the handle and the blades are in vertical planes.

The main object of my invention is to provide means for rotating the knife blades 90 degrees from their normal vertical planes without turning the body of the knife as a whole, thereby permitting the user to perform the slicing in either vertical or horizontal planes while holding the knife by its handle or by gripping the body of the knife in the manner intended for vertical slicing.

Another object of the invention is to provide means for preventing release or removal of the blades except when the blades are in the vertical position relatively to their housing and parallel to the release means.

Another object of the invention is to provide a turret mounted on the forward end of the knife, rotatable about the longitudinal axis of the knife housing, for quick manual adjustment of the blade positions in either vertical or horizontal positions.

Other objects and advantages of the invention will be apparent from the drawings and following description.

In the drawings:

FIG. 1 is an elevational side view of one form of power operated knife embodying my invention.

FIG. 2 is a top plan view of the same.

FIG. 3 is a longitudinal vertical sectional view, on an enlarged scale, in the plane of the line 3—3 of FIG. 2.

FIG. 4 is a top plan view of the lower housing member and the parts mounted therein, the upper housing and handle being omitted for clarity.

FIG. 5 is a transverse vertical sectional view in the plane of the line 5—5 of FIG. 4, showing blade carriers and the blades in vertical cutting positions.

FIG. 6 is a view similar to FIG. 5, showing the same parts when the blades are in horizontal cutting positions.

FIG. 7 is a transverse vertical sectional view in the plane of the line 7—7 of FIG. 4, showing the carriers and the blades in their vertical cutting positions.

2

FIG. 8 is a view similar to FIG. 7 showing the same parts when the blades are in horizontal cutting positions.

FIG. 9 is an elevational side view of one of the blade retaining levers and carrier.

FIG. 10 is a sectional view in the plane of the line 10—10 of FIG. 9.

In that embodiment of the invention shown in the drawings, the knife 10 as a whole comprises a lower housing 11, upper housing 12 with integral handle 13, and reciprocated blades 14 mounted in the forward ends of the housing members. A switch button 15 is mounted in the upper housing and a blade release button 16 in the lower housing. A turret 17 is rotatably mounted on the forward end of the knife body. As shown in FIGS. 3 and 4, the turret is cup-shaped, with its open face directed forwardly, and its inner face provided with an opening 18 shaped to receive the tangs 19 of the blades 14 and projections 20 on the tangs, as shown in FIGS. 5 and 6. The blades 14 are provided with grease guards 21 each attached to the outer side of a blade adjacent the tangs 19, said guards 21 partially entering the turret 17 as shown in FIG. 4.

Before describing the means for rotating the blades 14 from vertical to horizontal planes, brief reference will be made to the mechanism for transmitting reciprocatory motion to the blades. The motor 22 as a whole has a shaft 23. A worm 24 on the end of the shaft 23 engages a worm gear 25 fixed on shaft 26. A pair of cams 27 are eccentrically fixed on the shaft 26 to rotate with the shaft, their working faces being 180° apart. The shaft is journaled in bearings 28 mounted in the gear housing 29. The cams 27 are located between the flanged downturned arms 30 which are integral parts of the driver bars 31 and transmit reciprocatory motion to the blade carriers to be described hereinafter.

The driver bars 31 are generally flat and vertically disposed in their rearward portions which engage the cams 27. The forward portion 32 of each driver bar is semi-cylindrical in transverse vertical section as shown in FIGS. 7 and 8. One of the driver bars 32 is provided with a slot 33 and the other with a slot 34 between its ends. The driver bar members 31 and 32 are connected together as indicated at 35. As shown in FIGS. 7 and 8, the slot 33 extends arcuately more than 90 degrees in the left hand driver member 32 from above a horizontal plane to the right of a vertical plane, and the slot 34 extends more than 90 degrees in the right hand driver 32 from left of the vertical plane to below a horizontal plane. These slots accommodate parts of the carriers to be described. Reinforcing ribs 36 are located in the driver members 32 at opposite sides of the slots 33, 34.

Two blade carriers 40 are generally semi-cylindrical on their outer surfaces, in transverse vertical section, and are located between the driver bar members 32 for rotative movement relatively to said bars. Each of the carriers 40 is provided with a centrally bored boss 41 which projects laterally from the carrier body 40. One boss 41 extends through the slot 33 of a driver bar 32 and the other boss 41 extends through the slot 34 of the other driver bar 32. Each carrier 40 is retained rotatably relatively to a driver bar by a retainer ring 42 mounted on the outwardly projecting portion of the boss 41, said retainer ring 42 being held in place by a spring 43 mounted in a groove 44 near the outer end of the boss 41.

A retainer stud 45 in the central bore of each boss 41 has a head 46 on its inner end. The stud 45 has pivotally mounted thereon a blade retainer 47 in the form of a flat lever, best shown in FIGS. 3 and 10. The lever is retained by the head 46 between the head and the inner surface of the carrier 40. The retainer lever 47 has a hook 48 formed on its free end to provide a curved edge 49 which engages the projection 20 on a blade tang 19.

Depending from the lever 47 is an arm 50 adapted to be contacted by the depressible blade release button 16 mounted in the bottom wall of the lower housing 11. A retainer spring 51 has one end 52 hooked through an aperture in the lever 47 and its other end attached to a part of the carrier 40, as shown in FIGS. 9 and 10, to normally hold the lever 47 in position wherein the hook 48 and edge 49 engage the projection 20 on the tang 19 of a blade 14.

The blade release button 16, shown in FIGS. 3, 5 and 6, is mounted in the bottom wall of the lower housing 11 in position to contact the arms 50 of the levers 47 of the two carriers 40 when the carriers are in the vertical positions shown in FIG. 5. When the blades are in the horizontal position of FIGS. 6, the button 16 cannot contact the arms 50 of lever 47. The button comprises a face 53, side walls 54 terminating in a flanged edge 55 which prevents the button from moving downwardly out of the housing, springs 56 which bear on the face 53 and housing wall 57, and normally urge the button in a downward direction, out of contact with the blade release lever arm 50. The upright actuating members 58 are located between the side walls 54 and springs 56 in positions to contact and lift the blade release lever arms 50.

The switch button 15 and switch actuating mechanism are the subject of a co-pending application Serial No. 469,208, filed July 2, 1965 of Harvey Korshak and myself, and therefore need not be described herein.

The turret 17 is turned manually to move the blades 14 into vertical or horizontal cutting positions. This movement rotates the carriers 40 relatively to the driver members 32 in arcuate paths limited by the movement of the bosses 41 in the driver slots 33 and 34, respectively. The blades are retained in their carriers by the engagement of hooks 48 and edges 49 with the projections 20 of the blade tangs 19. When the blades are in the horizontal cutting positions of FIGS. 6 and 8, the levers 47 cannot be disengaged from the tangs 19. When the blades are in the vertical cutting positions of FIGS. 5 and 7, they can be released by depressing the blade release button 16 to thereby move the actuating portions 58 of the button into contact with the arms 50 of the levers 47, causing the lever to pivot about the stud 45 and to raise the hook 48 and edge 49 out of engagement with the projections 20 on the tangs 19 of the blades. The button 16 returns to undepressed position under influence of the springs 56, and the levers 47 resume normal positions under influence of the long retainer spring 51.

In describing the invention, reference has been made to a particular example embodying the same, but I wish it to be understood that the invention is not limited to the construction shown in the drawings and that various changes may be made in the construction and general arrangement of parts without departing from the invention defined by the claims.

I claim:

1. In a power operated knife having a housing, power transmission means in the housing, a knife blade, and blade driving means detachably connecting said knife blade to said transmission means, means for adjusting the position of the blade relatively to the housing for cutting material in planes at an angle to each other comprising

- (a) a turret rotatably mounted on one end of the housing having an opening therethrough for passage of the blade tang into the housing,
- (b) a blade carrier rotatably mounted adjacent the blade driving means in axial alignment with the turret, and
- (c) cooperating means on the carrier and driving means limiting the rotatable movement of the carrier in opposite directions.

2. The power operated knife defined by claim 1, in which the opening in the turret is defined by edges which

engage the side surfaces of the blade and cause the blade and carrier to turn about their longitudinal axes when the turret is rotated.

3. The power operated knife defined by claim 1, in which the cooperating means on the carrier and driving means for limiting the rotatable movement of the carrier in opposite directions comprises a slot in one of said cooperating members and a boss on the other of said members extending through the slot.

4. A power operated knife comprising

- (a) a housing,
- (b) power transmission means in the housing,
- (c) a pair of blades reciprocable relatively to each other,
- (d) blade driving means operatively connected to said transmission means,
- (e) a pair of carriers located between said blade driving means,
- (f) means connecting the carriers and driving means for rotative movement of the carriers relatively to said driving means, and
- (g) rotatable means on the housing through which said blades extend into engagement with the carriers for rotating the blades and carriers about their longitudinal axes to adjust the cutting positions of the blades relatively to the housing.

5. The power operated knife defined by claim 4, in which the blade driving means comprise a pair of driver rods which are arcuate in transverse section and generally complementary to the adjacent blade carriers.

6. The power operated knife defined by claim 4, in which the blade driving means comprise a pair of driver rods each having a generally flat rearward portion engaging the power transmission means and an arcuate forward portion generally complementary to the carriers.

7. The power operated knife defined by claim 4, in which the blade driving means comprise a pair of driver rods which are arcuate in transverse section adjacent the carriers and each provided with a slot, and in which each carrier is provided with a radially extending boss slidably in the slot in one of the driver rods, whereby the rotative movement of the carrier relatively to the driver rod is limited.

8. The power operated knife defined by claim 7, in which the arcuate length of the driver slots permits the carriers and blades to rotate 90 degrees about their longitudinal axes.

9. A power operated knife comprising

- (a) a housing,
- (b) power transmission means in the housing,
- (c) a blade reciprocably mounted in the housing,
- (d) blade driving means operatively connected to said transmission means,
- (e) a blade carrier rotatably mounted adjacent the driving means,
- (f) means on the housing for manually rotating the blade and carrier for adjusting the cutting positions of the blade to either a vertical or a horizontal plane relatively to the housing,
- (g) a blade retaining lever pivotally connected at one end to the carrier and having a free end in engagement with the blade,
- (h) means connecting the carrier and driving means for limited rotative movement of the carrier relatively to the driving means, and
- (i) a blade release button depressibly mounted in the housing for contacting the blade retaining lever and releasing the blade for removal when the blade is in its vertical plane position.

10. A power operated knife comprising

- (a) a housing,
- (b) power transmission means in the housing,
- (c) a pair of blades reciprocable relatively to each other,
- (d) blade driving means operatively connected to said transmission means,

- (e) a pair of carriers located between said blade driving means,
- (f) means on the housing for manually rotating the blades and carriers for adjusting the cutting positions of the blades to either vertical or horizontal planes 5
- (g) a blade retaining lever pivotally connected at one end to each carrier and having a free end in engagement with a blade,
- (h) means connecting the carriers and driving means for limited rotative movement of the carriers relatively to the driving means, and
- (i) a blade release button depressibly mounted in the housing for contacting the blade retaining levers and 10

releasing the blades for removal when the blades are in their vertical plane positions relatively to the housing.
